UNITED STATES PATENT OFFICE.

SIDNEY G. BROWN, OF NORTH ACTON, ENGLAND, ASSIGNOR TO S. G. BROWN LIMITED,
OF NORTH ACTON, ENGLAND.

DESIGN FOR A SOUND AMPLIFIER OR SIMILAR ARTICLE.

Application filed October 21, 1924. Serial No. 11,136. Term of patent 7 years.

To all whom it may concern:

Be it known that I, SIDNEY GEORGE BROWN, F. R. S., a subject of the King of Great Britain, residing at North Acton, in the county of Middlesex, England, engineer, have invented a new, original, and ornamental Design for a Sound Amplifier or Similar Article, of which the following is a specification, reference being had to the

accompanying drawing, forming part thereof.

The figure is a plan view of a sound amplifier or similar article showing my new design.

I claim:

The ornamental design for a sound amplifier or similar article as shown.

S. G. BROWN.
